UNITED STATES PATENT OFFICE.

JOHN L. PARKES, OF CHICAGO, ILLINOIS.

PRIMING DEVICE.

1,176,777.

Specification of Letters Patent. Patented Mar. 28, 1916.

Application filed January 12, 1914. Serial No. 811,543.

To all whom it may concern:

Be it known that I, JOHN L. PARKES, a citizen of the United States, and a resident of the city of Chicago, county of Cook, and State of Illinois, have invented certain new and useful Improvements in Priming Devices; and I do hereby declare that the following is a full, clear, and exact description of the same, reference being had to the accompanying drawings, and to the numerals of reference marked thereon, which form a part of this specification.

Oftentimes internal combustion engines are difficult to start owing to the introduction thereto of a poor fuel mixture from the carbureter, and consequently, the engine must be cranked a number of times to introduce and eject various charges of mixture until one proper for ignition is introduced. However, the difficulty in starting is not always the fault of the carbureter, as the latter may be adjusted to introduce proper mixtures to the engine when the same is running, and the cylinders are warm, whereas atmospheric and climatic conditions may have an effect upon the engine and carbureter as to prevent immediate starting of the engine when the same is cold. It is a well known expedient when such difficulty is encountered, to prime the cylinders of the motor by introducing liquid hydro-carbon through pet cocks in each one of the cylinders, after which, by switching on the spark and giving the engine a slight turn, it is started in operation.

This invention relates to a means for priming each cylinder of the motor by mechanism attached on the dash, thereby not requiring the operator, as, for instance, in an automobile, to dismount from his position to raise the hood of the car or be otherwise inconvenienced in the priming operation.

It is an object of this invention also, to provide a device for pumping hydro-carbon fuel into the various cylinders of the motor regardless of the conditions of pressure therein.

It is also an object of this invention to provide piping connections for each cylinder of the engine, whereby fuel may be pumped therethrough under pressure, to and into each one of the cylinders consecutively, as, for instance, in their firing order, or as otherwise desired.

It is also an object of this invention to construct a device wherein a movement of a

plunger serves to open an admission valve for hydro-carbon fuel into a cylinder containing the plunger and wherein reverse movement of said plunger serves to force said fuel under pressure, outwardly from said cylinder to the respective cylinders of a hydro-carbon engine.

It is also an object of this invention to provide a device for introducing fuel under pressure to the respective cylinders of a hydro-carbon engine and wherein suitable check valves are provided in the pipe lines connected to the cylinders to permit an increase of pressure therein to any desired amount, determined by the number of actuations of the plunger.

It is furthermore an object of this invention to construct a device wherein fuel may be introduced to the cylinders of a hydro-carbon engine under pressure independently of the carbureting mechanism, and directed within said cylinders toward the ignition means.

It is finally an object of this invention to construct a device for priming the cylinders of an engine consisting of few parts, and particularly, so assembled as to facilitate ready attachment and easy removal to or from an automobile or other vehicle or support upon which the same may be connected.

The invention (in a preferred form) is hereinafter more fully described and defined in the accompanying drawings and specification.

In the drawings: Figure 1 is a conventional side elevation of the gasoline motor of an automobile showing a device embodying the principles of my invention connected thereto and mounted on the dash of the automobile. Fig. 2 is a longitudinal central vertical section, with parts in elevation, taken through the feed and pressure producing means of my invention. Fig. 3 is a section on line 3—3 of Fig. 2, with parts in elevation. Fig. 4 is a section on line 4—4 of Fig. 2, with parts in elevation. Fig. 5 is a section on line 5—5 of Fig. 2. Fig. 6 is a fragmentary top plan view of the plunger element. Fig. 7 is a fragmentary view, partly in section, of the outer end of the plunger element and cylinder therefor, illustrating the construction. Fig. 8 is a sectional view, illustrating the pivoted finger grip on the outer end of the plunger element. Fig. 9 is a view, partly in section and partly in elevation, illustrating the con-

struction of the union connection threaded into the cylinders of the motor. Fig. 10 is a top view of the union element 6. Fig. 11 is a fragmentary view, partly in section, illustrating a modification of the union element of Fig. 9. Fig. 12 is a detail section partly in elevation taken on line 12—12 of Fig. 2.

As shown in the drawings: The reference numeral 1, indicates as a whole a gasolene motor having four cylinders, denoted respectively as 2, 3, 4, and 5. A union connection 6, is threaded into each one of said cylinders, and in each case said connection at its upper end has threaded therein a pet cock 7. A relatively long pressure cylinder 8, is mounted in the dash 9, of the automobile and is supported therein through an aperture therethrough in inclined position by a pair of washers 10 and 11, respectively, the faces of each of which are angled for the purpose, as mentioned, of maintaining the cylinder 8, in inclined position. At its point of attachment said cylinder 8, is slightly reduced in diameter on its outer periphery in order to project through the apertures in said washers 10 and 11, and afford a shoulder against which said washer 10, may abut to limit the projection of said cylinder 8, therethrough. As shown in Fig. 7, the reduced end of said cylinder 8, is also provided with a longitudinal slot 12, slidably engaged by a pin 13, secured on the washer 11, to prevent rotational movement between the cylinder and the washer, and threads are also provided on the outer reduced end of said cylinder to receive a clamping nut 14, thereon.

When the device is mounted in the dash or other support the washer 10, is positioned on one side of the dash, and the washer 11, on the other, and the cylinder 8, is then inserted therethrough with the groove 12, therein engaging the pin 13, and the clamping nut 14, is threaded on the end of said cylinder and bears against the washer 11, to draw the elements tightly together. A finger grip 15, is pivotally mounted on the end of a plunger 16, slideable in said cylinder 8, and is provided with a set screw 17, adapted to engage in an indent 18, in the extremity of said plunger to maintain the finger grip in the position as shown in Fig. 2, and to release the same into a position as shown in Fig. 7, to permit insertion of the washers 10 and 11, and clamping nut 14, thereover when desired. The outer surface or periphery of the cylinder 8, beyond that portion extending through the washers and nut already mentioned, is of hexagonal contour, as shown clearly in Figs. 3, 4, and 5, as this enables a purchase to be obtained upon the cylinder to retain the same from rotation when the clamping nut 14, is being threaded thereon.

Suitable packing 19, surrounds the plunger, within the upper end of the cylinder and is retained by a packing gland 20, threaded within said cylinder and bearing against the packing. A hollow nut or union 21, is threaded into a suitable aperture in said cylinder 8, and contains a spring pressed ball 22, affording a check valve impelled downwardly by a spring 23, the upper end of which seats against a ball 24, which is free to move upwardly and loosely through the aperture in said cylinder.

As clearly obvious, the purpose of the ball 24, is merely to afford seating means for the spring 23, whereby the ball closure 22, may be normally impelled into a position to close communication through the passage in said union element 21. In order to release the ball 24, whereby pressure within the intake fuel supply line 25, may raise the elements contained in said union 21, to permit a flow of fuel therewith, said plunger 16, on its under side is provided with a relatively long recess 26, so that as the curved shoulder 27, at one end thereof, passes over the ball 24, as the plunger is drawn outwardly, the ball 24, will spring upwardly into contact with the recessed portion of the plunger, thus releasing the pressure on said spring 23, and permitting the pressure in the gasolene line 25 to raise the ball closure element 22, and permit a flow of fluid into the cylinder 8. A check valve 25^a, of any conventional type or construction, is provided at the junction of the pipe 25, with the main fuel line leading to the carburetor to prevent a reverse flow through said pipe 25. For the purpose of limiting the amplitude of movement of said plunger 16, a stop 28, is threaded into the under side of said cylinder and projects into the recessed portion 26, of the plunger, and is adapted to contact the shoulder 29, at the end of said recessed portion 26, to limit the outward adjustment of said plunger. As shown, said stop element 28, is threaded into the cylinder, thus permitting the same to be removed therefrom when it is desired to withdraw the plunger entirely from the device for any purpose whatsoever. Threaded into said cylinder 8, on the upper side thereof, is a plurality of union connections corresponding in number to the number of cylinders on the motor, and denoted respectively by the reference characters 2^a, 3^a, 4^a, and 5^a, and are connected by suitable pipes 2^b, 3^b, 4^b, and 5^b, to unions 30, one each threaded into the union elements 6, heretofore mentioned, which are, in turn, secured in the respective cylinders 2, 3, 4, and 5. Contained within each of said union elements 2^a, 3^a, 4^a, 5^a, and 30, are spring pressed ball or check valves 31, and 30^a, respectively, which prevent a reverse flow into the cylinder 8, from any of the respective pipes connected to said elements. A peripheral

groove 32, is provided in said plunger element 16, and affords communication for a flow of fluid from the recessed portion 26, to a recessed or flattened portion 33, on the upper surface of said plunger element. Likewise it is to be noted that the end of the plunger element 16, beyond the shoulder 29, heretofore mentioned, is reduced in diameter, in order to permit an easy flow of fluid 10 around said end to or from the recessed portion 26, of the plunger element when said plunger is moved within the cylinder. Said recess or flattened portion 33, on the upper side of the plunger element, is of a length less than the distance between the apertures in the upper side of the cylinder 8, into which said union elements are threaded, so as to at no time permit communication between adjacent passages through said recessed portion 33, of the plunger. A recess 33^a, is formed within the cylinder 8, adjacent to and communicating with the outlet to the union connection 2^a, in order to prevent the occurrence of excessive pressure 25 which would otherwise be the result within the cylinder to prevent movement of the plunger, when the plunger has been drawn back into its extreme outer position prior to an initial forward movement. This is due 30 to the fact that the recess 33, is withdrawn past the outlet 2^a, and inasmuch as the cylinder 8, is filled with liquid which is practically incompressible, the initial movement of the plunger would be resisted due to the 35 incompressibility of the fluid. Such a condition, however, is obviated by the provision of the recess 33^a, which effects communication between the recess 33, of the plunger and the outlet 2^a, when the plunger is withdrawn 40 into its extreme outer position.

The relatively large union elements 6, which are threaded into the heads of the motor cylinders, are each provided with passages 34 and 35, respectively, the passage 45 34, affording communication between the cylinder and the pet cock 7, and the passage 35, adapted to receive the fluid from one of the aforementioned pipes through the union 30, to spray the same into the cylinder, and accordingly the lower end of said passage 50 35, is narrowed to insure the introduction of the fuel into the cylinder in a sprayed condition. In the modification illustrated in Fig. 11, a laterally directed passage 36, communicates with the passage 35, whereby the fuel may be sprayed laterally in the cylinder and preferably toward the spark plug or other ignition means, and, of course, a suitable mark or indication may be provided on 55 the upper visible portion of the elements to designate the position of said laterally directed passage 36, within the cylinder.

The operation is as follows: The device, as shown in the position illustrated in Fig. 60 2, is closed, and no flow of fluid takes place

therethrough. However, when it is desired to prime the cylinders of the motor, the plunger 16, is actuated back and forth whereupon the following sequence of operations take place with each complete movement thereof. As the shoulder 27, on the plunger passes over the ball 24, the same is released, thereby releasing the ball closure 22, and permitting the fuel from the inlet supply line 25, to flow upwardly and into 70 the plunger cylinder 8, and, of course, with the plunger fully retracted a considerable quantity of fuel may be contained therein. When the plunger is thrust inwardly into the cylinder 8, the contained fluid is, of 75 course, placed under a condition of pressure, owing to said valve 22, connected to the inlet, being closed, and consequently a flow from the cylinder 8, can only take place through one of the union valve elements 2^a, 80 3^a, 4^a, or 5^a, depending, of course, with which valve thereof, the flattened or recessed portion 33, of the plunger element is in register.

It is obvious that as the plunger is moved 90 from its retracted position inwardly within the cylinder that the recessed portion 33, will successively communicate with the passages leading to each of the aforesaid union valve elements, thus forcing a certain quantity of fuel to the corresponding cylinders of the engine to which said elements are connected, and, of course, to only one cylinder at a time. By repeating the operation of moving the plunger in and out in its 95 containing cylinder any desired amount of fuel may be pumped to the engine cylinders, and any back pressure due to compression in one or more of the cylinders, may readily be overcome. Inasmuch as it is desirable to force fuel to only one cylinder at a time and this operation only taking place when the recessed portion 33, of the plunger element is in register with one of the passages for certain of said union valve elements, said plunger element must act at all other times to maintain said passages closed. For this purpose a spring pressed ball 37, is provided contained within a hollow 100 threaded plug member 38, which is threaded 110 into the lower side of the cylinder 8, in a position such that the ball 37, may bear upwardly against the recessed portion 36, of the plunger, and thus force the plunger into close contact with the passages in the upper 115 120 side of the cylinder to maintain the same closed.

The plunger may be withdrawn into retracted position if desired and left thus for operation in an emergency, the relation between the pressure cylinder and the motor cylinder of course being the same when the plunger is in retracted position as when in normal position.

I am aware that various details of con- 125 130

struction may be varied through a wide range without departing from the principles of this invention. I therefore do not purpose limiting the patent granted otherwise than necessitated by the prior art.

I claim as my invention:

1. In a device of the class described a cylinder, a plunger slidable therein, recessed portions thereon adapted to open the inlet to said cylinder and the outlets therefrom and said portions so disposed to shut off the inlet to said cylinder and open communication to one each of said outlets in successive order.
- 10 2. In a device of the class described a cylinder, a plurality of outlets therein and an inlet thereto, a plunger slidable in said cylinder adapted to control the opening and closing of said inlet and outlets, a pair of washers adapted to support said cylinder in inclined position, and means clamping the same in such position.

3. In a device of the class described a cylinder, washers having inclined faces to support the cylinder in inclined position, 25 and a pin on said cylinder adapted to engage a groove in a washer to prevent relative movement therebetween.

4. In a device of the class described a cylinder, a piston therein, means supporting the cylinder in inclined position, a pivoted finger grip on said piston adapted to be moved into position for insertion through said supporting means, and means on said grip to secure the same immovably on said piston.

In testimony whereof I have hereunto subscribed my name in the presence of two subscribing witnesses:

JOHN L. PARKES.
